INVENTOR

BY *W. Bond*
ATTORNEY

UNITED STATES PATENT OFFICE.

GEORGE EDWARD LINTON, OF SUDBURY, ONTARIO, CANADA.

CROSSHEAD.

Application filed January 29, 1921. Serial No. 441,046.

To all whom it may concern:

Be it known that I, GEORGE E. LINTON, a citizen of the Dominion of Canada, residing at Sudbury, in the District of Sudbury and Province of Ontario, have invented certain new and useful Improvements in Crossheads, of which the following is a specification.

This invention relates to improvements 10 in cross heads for use in mine shafts in which buckets are being used, an object of the invention being to provide a cross head which will properly guide the bucket centrally of the shaft and prevent lateral swinging 15 of the bucket during the raising or lowering of the same.

Further objects of the invention are to so construct the cross head that in the event of its sticking or jamming on the slides of 20 the shafts, then the bucket will be maintained in a proper position relatively to the cross head and the hauling rope will sag during the continued unwinding of the hauling rope, so indicating to the operator of 25 the hauling or winding engine that the cross head is not functioning properly, and that investigation should therefore be made.

It is also intended to construct the cross head so that it will interlock or become disengaged with or from a suitable clamping 30 member on the hauling rope, and to provide suitable stop members which will co-act with the cross head so as to maintain the same at a safe distance above the bottom of 35 the shaft, and disengaged from the clamping member so permitting the bucket to be lowered for filling purposes and without any possibility of the cross head ever striking or interfering with the operation of any 40 miners at the bottom of the shaft.

So that my invention will be properly understood, I have illustrated a preferred embodiment of the same, which will now be described in detail, after which the novel features 45 will be pointed out in the appended claims.

In the accompanying drawings, Figure 1 is a sectional perspective view of a part of a mining shaft, showing the cross head engaging with the slides, and the bucket suspended below the cross head.

Figure 2 is a sectional elevation of a small portion of the shaft showing the cross head slidably engaging the slides and the bucket in the process of being raised.

Figure 3 is a perspective view of one portion of the locking means which co-acts with a clamping member of the hauling rope.

Figure 4 is a perspective view of a lever which controls the operation of the locking 60 means.

1 indicates a mine shaft lined with suitable lagging 2, and on diametrically opposite sides of the shaft slides 3 are secured to the lagging.

My improved cross head 4 consists of a pair of horizontally disposed bars 5 spaced in parallelism and formed with recesses 6 in the ends thereof. The bars 5 are connected adjacent to the ends with vertical 70 bars 7, the outermost of which extend into the inner ends of the recesses 6, and the cross head is completed by diagonal struts 8, which brace the several bars of the cross head.

The slots 6 slidably engage with the slides 3, so that the cross head is capable of being elevated and lowered within the shaft.

On the lower transverse bar 5 of the cross head, locking means are provided to co-act 80 with the clamping member 9 which is adjustably mounted on the hauling rope 10, and this locking means consists of two portions which are similar, so that I will only describe one of the same.

One of the said portions consists of a plate 11 which is spaced from the bar 5 of the cross head, but connected therewith by columns 12, and two columns are used on that edge of the plate adjacent to the slide 90 3. The opposite edge of the plate 11 is rigidly attached to the lower ends of two brackets 13, the upper ends of which are rigidly connected to the bar 5.

On the plate 11, brackets of suitable angle 95 or like shape 14, are mounted, and a lever 15 is pivotally attached intermediate of its length to the bracket 14. The lever 15 consists of an upper and lower plate 16 and 17 attached by a web 18, and it is through this web that the pivot pin of the lever passes.

Below the plate 17, leaf springs 19 are located, and attached at one end to the plate 11, the other end bearing against the plate 17 and tending to hold the lever 15 in a locking position.

The lever 15 will be rocked under certain working conditions and to allow this operation being performed, I provide a second lever 20, which is pivoted intermediate of 110

its length to a bracket 21 which is secured to the lower face of the plate 11 and extends downwardly therefrom.

The lever 20 may be of suitable shape, but

5 I prefer to make the top with two converging flat faces 22 and an under web 23, which strengthens the lever and provides a suitable member through which the pivot pin of the lever will pass.

10 This lever is connected at one end to the lever 15 by a bolt 24, which slidably passes through the plate 11, and the opposite end of the lever 20 is bifurcated as illustrated at 25 and slidably engages the slide 3. On the 15 slide 3 I provide an adjustable stop member 26.

When the cross head 4 is being lowered, the clamping member 9 on the rope 10 will be engaged by the plate 16 of the locking

20 members. If the cross head should jamb, or fail to slide on the slides 3, the bucket would remain suspended from the clamp 9, and would not continue being lowered, and as the hauling rope 10 was unwound from 25 the winding engine, or other suitable lowering machinery, then the upper portion of the rope 10 would sag and so indicate to the engineman that something was wrong, and required attention.

30 Should the cross head 4 and bucket descend in a normal manner, then as the bucket neared the bottom of the shaft, the bifurcated end 25 of the levers 20, would engage the stops 26, so that the levers 20 would 35 be rocked about their fulcrum points, and this rocking motion would be transmitted through the bolts 24 to the levers 15.

As the levers 15 are rocked, the upper plates 16 become spaced apart, thus allowing 40 the clamp 9 to pass therebetween, so that the bucket will continue to be lowered, although the cross head 4 will have become arrested by the stop members 26, and will be held at some distance above the bottom of the shaft.

45 When the bucket has been filled and is being raised, the clamp 9 will freely pass between the two plates 16 of the levers 15, and the clamp will now engage the under face of the lower bar 5 of the cross head 4.

50 As the hauling rope is wound up, the cross head 4 will be elevated simultaneously with the bucket, and as soon as the levers 20 are disengaged from the stop members 26, the springs 19 will return the levers 15 to a 55 normal position in which the adjacent edges of the plates 16 will have slightly approached each other and be in a locking position.

The cross head will hold the rope 10 centrally within the shaft 1, and prevent lateral swaying of the rope and bucket, and the interlocking means carried by the cross head will be automatically operated to engage or disengage the clamp on the hauling rope, so 65 providing a safety device for the cross head,

and preventing damage being done both to the shaft and to miners working therein.

I claim:

1. A safety cross head having edge recesses designed to slidably engage the slides of a mine shaft, and through which a hauling rope passes, a clamp on the hauling rope, and locking means on the cross head movable on pivots perpendicular to the rope and said levers co-acting with the clamp. 75

2. A safety cross head having edge recesses designed to slidably engage the slides of a mine shaft, and through which a hauling rope passes, a clamp on the hauling rope, pivotally mounted locking levers movable on pivots perpendicular to the rope and said levers co-acting with the clamp, means for rocking the levers to disengage the clamp, and means for returning the levers to a normal position. 80

3. A safety cross head having edge recesses designed to slidably engage the slides of a mine shaft, and through which a hauling rope passes, a clamp adjustably mounted on the hauling rope, pivotally mounted locking levers movable on pivots perpendicular to the rope and said levers co-acting with the clamp, levers for rocking the said levers to disengage the clamp, and means for returning the first said levers to a normal 95 locking position. 90

4. A safety cross head having edge recesses designed to slidably engage the slides of a mine shaft, and through which a hauling rope passes, a clamp on the hauling rope, pivotally mounted levers movable on pivots perpendicular to the rope and said levers co-acting with the clamp, means for rocking the levers to disengage the clamp, and spring means for returning the levers to a 100 normal position when the last said means are inoperative. 105

5. A safety cross head having edge recesses designed to slidably engage the slides of a mine shaft, and through which a hauling rope passes, a clamp on the hauling rope, pivotally mounted levers movable on pivots perpendicular to the rope and said levers co-acting with the clamp, pivotally mounted levers, bolts connecting the first said levers to the second said levers, means for rocking the second said levers and means co-acting with the first said levers to return the same to a normal position when the last said means are inoperative. 110 115

6. A safety cross head having edge recesses designed to slidably engage the slides of a mine shaft, and through which a hauling rope passes, a clamp on the hauling rope, pivotally mounted levers movable on pivots perpendicular to the rope and said levers co-acting with the clamp, a second set of pivotally mounted levers operatively connected to the first set, adjustable stop members on the slides, and means engaging with 125 130

the first set of levers to return the same to a normal position.

7. A safety cross head having edge recesses designed to slidably engage the slides 5 of a mine shaft and through which a hauling rope passes, said slides, plates carried by the cross head, a pair of levers pivoted to the top of the plates, a pair of levers pivoted to the under sides of the plates, means 10 for connecting the levers of each plate, the last said levers having bifurcated ends slidably engaging the slides, adjustable stops on the slides, and a clamp on the hauling rope. 15

8. A safety cross head consisting of a pair of transverse members having edge recesses, slides for cooperation with said recesses, vertical members holding the transverse mem-

bers in spaced relation, diagonal struts between the transverse members and between the vertical members and locking means carried by the cross head and embodying levers disposed in opposed relation and connected together, one set of levers adapted to slidably engage the guide of the cross head, and stops on the slides to prevent the lowering 20 of a bucket, in the event of the cross head jamming in a mine shaft. 25

In testimony whereof I affix my signature in the presence of two witnesses.

GEORGE EDWARD LINTON.
